UNITED STATES PATENT OFFICE.

JOHN MARTENS, OF CHICAGO, ILLINOIS.

HOT-WATER HEATER.

Specification of Letters Patent.

Patented Oct. 3, 1916.

1,199,805.

Application filed July 17, 1915. Serial No. 40,498.

To all whom it may concern:

Be it known that I, JOHN MARTENS, a citizen of the United States, residing at Chicago, in the county of Cook and State of Illinois, have invented a certain new and useful Improvement in Hot-Water Heaters, of which the following is a full, clear, concise, and exact description, reference being had to the accompanying drawings, forming a part of this specification.

10 My invention relates to hot water heaters and aims to provide an improved heater of inexpensive construction and of increased efficiency.

15 Other and further objects and advantages will be apparent from the following specification.

In carrying out my invention I employ the down draft principle in order to employ and utilize as much of the heat from 20 the burner as possible. I also provide an auxiliary air supply for the combustion chamber to provide an additional amount of air and to control the draft on the burner.

25 In the accompanying drawings which form a part of the present specification, Figure 1 is a longitudinal vertical section of one form of my heater; Fig. 2 is a horizontal section taken on the line 2, 2, of Fig. 30 1; Fig. 3 is a fragmentary detail view showing the manner of attachment of the baffle and the channel to the wall of the combustion chamber; Fig. 4 is a vertical longitudinal section of another form of my invention; Fig. 5 is a fragmentary view showing the vaporizer applied to the top of the heater; and Fig. 6 is an enlarged sectional view showing the manner in which the channel is applied to the interior of the heater.

35 The heater shown in Fig. 1 consists essentially of an outer shell 1 which has connected thereto the inlet pipe 2 adjacent the bottom, a hot water delivery pipe 3, and a pipe 4 leading to an auxiliary heater. A 40 drain cock 5 may also be connected to the bottom of the heater to drain the same to prevent freezing. An inner shell 6 which is of considerably less length than the outer shell 1 is secured at its lower end 45 by means of the flared connection 7 to the bottom of the shell 1 to form a combustion chamber 8 within which is provided a suitable burner, such as the gas burner 9. A 50 plurality of holes 10 are cut in the side walls of the shells 1 and 6 to provide air for the burner 9, the bottom of the combustion

chamber being closed by a cap or closure 11. The smoke or exhaust flue 12 passes through the outer shell 1 and is secured to the inner shell 6 at a point well toward the bottom 60 of the constricted part of the combustion chamber. A heating tube 13 which may consist of one or more lengths of tubing is connected by a nipple 14 at the bottom of the water space between the shells 1 and 6, and 65 at its upper end projects through the top of the shell 6 so as to discharge the water heated in the tube into the top of the water space and adjacent the delivery pipe 3. An auxiliary or fresh air flue 15 is connected to 70 the interior of the shell 6 near the top thereof. The position of the flue 15 may be varied in its position up or down without departing from the invention, in order to suit conditions. This fresh air flue 15 is provided 75 with a damper 16 so that the amount of fresh air drawn into the combustion chamber may be properly regulated. The smoke flue 12 is also provided with a damper 17 for controlling the draft upon the burner 9. 80

I have found that in heaters of this type there will be a considerable condensation or sweating upon the interior walls of the heater when the fire is first started up. This condensation runs down into the bottom of the combustion chamber and drips upon the burner, and is found to be very objectionable. To obviate this I employ the channel shown on an enlarged scale in Fig. 3, consisting of the U-shaped member 18 attached to the inside of the wall 6 and forming a suitable gutter for conducting the condensation and moisture from the wall 6 into the smoke flue 12. A suitable opening may be provided in the bottom of the smoke flue 95 12 to draw out such moisture and condensation as may be collected therein.

In order to guide the products of combustion to the top of the heating chamber formed by the shell 6, I employ a suitable 100 baffle. In Fig. 1, I have shown this baffle as comprising a plate 19 which is secured at its lower end to the channel member 18 and forming between itself and the wall 6 a suitable 105 passage for the discharge of the products of combustion. The lower end of the plate 19 may be bolted to the channel 18 as shown in Fig. 3, or secured in any other suitable manner, the top of said plate being 110 held against the side of the shell 6 by means of the tube 14. It can thus be seen that a suitable passage for the products of com-

bustion is formed up through the shell 6 and down between the plate 19 and the side of the shell 6.

In the form of the device shown in Fig. 5 the plate 19 has been replaced by an inner shell 20 which is closed at the top and secured at the bottom to the channel 18. The shell 20 is apertured at the side opposite the flue 12 as shown at 21. This aperture 21 10 may be placed at any convenient point on that side of the shell 20, the hot air being trapped above the opening to a certain extent. The channel member 18 is cut away at 22 at the point adjacent to the smoke flue 12 so that the moisture and condensation 15 may readily escape from the channel member 18.

It is often desirable to distil a certain amount of water for drinking purposes and 20 for this purpose I employ a mechanism shown in Fig. 5 in connection with the heater previously described. A supplemental shell 22 is secured to the top of the shell 1 in any suitable manner and forms a 25 vaporizing chamber which is in communication with the top of the water heater through a suitable float valve 23 which maintains a definite level of water in the vaporizing chamber. A suitable man-hole 24 closed by 30 a screw-cap 25 provides access to the interior of the vaporizing chamber so that the same may periodically be cleaned. The delivery pipe 3 and the auxiliary connection 4 may pass down through a vaporizing chamber or may be connected to the side of the shell 1, as desired. A suitable vapor delivery pipe 26 which may be controlled by a valve 27 conducts the steam generated in the vaporizing chamber to a 40 suitable worm or condenser if the water is to be distilled or to any other point if the steam or vapor is to be otherwise employed.

The float valve 23 is required in order to maintain a free steaming or vaporizing surface in the vaporizing chamber. The water within the main shell 1 being under pressure of the mains will always tend to fill the vaporizing chamber until the same is cut off by closure of the valve 23.

50 I do not intend to be limited to the precise details of construction shown and described as I consider that modifications and variations will at once suggest themselves to those skilled in the art.

55 What I claim as new and desire to protect by Letters Patent of the United States is the following:

1. In a water heater, a straight cylindrical outer shell having a closed top, a straight cylindrical inner shell forming a combustion chamber, said inner shell being also closed at its top, said shells being joined together at their lower ends to form a water space between them at the sides and between the tops of said shells, a longitudinal

heating tube having a length of pipe extending vertically, said pipe being contained in said inner shell, a burner adjacent the bottom of said shells and arranged to heat said pipe, said pipe being connected at its 70 lower end to the lower part of said water space and having its upper end extending through the top of the inner shell to a point adjacent the top of the outer shell, a flue extending through both of said shells near 75 the bottom thereof and a baffle contained within said inner shell and extending longitudinally thereof to a point adjacent the top of said inner shell, said baffle being interposed between the fire and said flue and 80 closing off communication with said flue except over the top thereof in order to cause the product of combustion to rise above the flue over the top of the baffle and then descend to pass out of the flue. 85

2. In combination an outer shell having a closed top, an inner shell forming a combustion chamber, said inner shell being closed at the top, said shells including a water space between them along the sides 90 and between the tops of the shells, a longitudinal heating tube contained in said inner shell, a burner adjacent the bottom of said shell and arranged to heat said tube, said tube being connected at its lower end to the 95 lower end of said water jacket and having its upper end extending adjacent the top of the other shell, a flue extending through both of said shells, a baffle for causing the products of combustion to rise above the 100 flue and then descend and an auxiliary flue extending through said shells adjacent the upper end of said combustion chamber.

3. In combination an outer shell, an inner shell forming a combustion chamber therein, 105 said shells including a water space between them, a longitudinal heating coil extending from the bottom of said water space, passing through said inner shell and extending adjacent the top of the outer shell, a burner at 110 the lower end of said combustion chamber, said burner arranged to heat said tube, a flue adjacent the bottom of said combustion chamber, said flue extending through both of said shells, an inclined channel extending 115 around the inner shell and having its lowermost side at the bottom of the smoke flue.

4. In combination an outer shell, an inner shell secured at its lower end to said outer 120 shell and forming a combustion chamber, said shells including a water space between them, a heating tube passing lengthwise through said inner shell, said tube connecting the bottom of the water space with the 125 top thereof, a smoke flue passing through both of said shells, an inclined channel extending around the inner shell and having its lowermost side adjacent the bottom of said flue, and a baffle for causing an upward 130

and return draft from the bottom of the combustion chamber to the flue.

5. In combination, a straight cylindrical outer shell having a closed top, a straight cylindrical inner shell having a closed top, said inner shell being of less length than said outer shell, said shells being secured together at their lower ends and forming a water space at top and sides between them,
10 a gas burner in said inner shell, a flue near the bottom of said shells, communicating with the space in said inner shell and lead-

ing the products of combustion to the outside of both shells and a baffle shutting off direct passage of the products of combustion from said burner with said flue, said baffle being attached below said flue and terminating adjacent the top of the inner shell and causing the products of combustion to rise in said inner shell and then pass 15 over said baffle to pass out at said flue.

In witness whereof, I hereunto subscribe my name this 16th day of July A. D. 1915.
JOHN MARTENS.
